UNITED STATES PATENT OFFICE.

BAILEY W. GEARY, OF BROCKTON, MASSACHUSETTS.

DIE FOR CUTTING SHOE-UPPERS.

SPECIFICATION forming part of Letters Patent No. 279,375, dated June 12, 1883.

Application filed March 5, 1883. (No model.)

To all whom it may concern:

Be it known that I, BAILEY WHITE GEARY, of Brockton, in the county of Plymouth, of the Commonwealth of Massachusetts, have invented a new and useful Improvement in Dies; and I do hereby declare the same to be described in the following specification and represented in the accompanying drawings, of which—

10 Figure 1 is a side elevation, Fig. 2 a bottom view, and Fig. 3 a vertical and longitudinal section, of a cutting-die provided with my invention, the nature of which is defined in the claim hereinafter presented. The die is to facilitate the cutting of what are termed "rights" and "lefts" in shoe-work, whether such be quarters or soles, or various other parts of a shoe. Fig. 4 denotes a set of rights and lefts of the kind made or cut by the die, 15 shaped as shown at A in the drawings.

This die has two opposite cutting-edges, *a*, *b*, one of which rests against the lower surface of a bearing-block, *B*, and is held thereto by a yoke, *C*, and by means of a clamp-screw, *D*, 20 which, provided with a head, *c*, extended from a handle, *E*, in manner as represented, screws into the yoke at its middle, the said yoke extending through the die at its opposite ends, as shown. By unscrewing the screw the 25 die may be reversed or turned over upon the block so as to bring downward the cutting-edge previously against it, and thus it will be seen that with the implement as made the die is adapted for use in cutting of either rights 30 or lefts, a pair of which of one kind is shown in Fig. 4.

To use the implement, it is to be forced, cutting-edge downward, upon a sheet of leather

or other suitable material, so as to cut through it.

I do not claim separate cutters adapted to opposite sides of and combined with a revolvable stock, as shown in the United States Patent No. 27,123, as I have a single cutter provided with two opposite cutting-edges, as set forth, and within and adapted to such cutter, as described, I have a yoke and a screw for securing it to a bearing-block, all of which differs materially from anything shown in such patent.

A cutting-die having upper and lower cutting-edges and rigidly fastened to a brace arranged within such die, and also having a handle capable of being inserted in the brace from either side of it, differs materially from any cutting-die which has a bearing-block for one of the cutting-edges to rest against, and the knife is borne up to such block by the screw of the handle and by the yoke which turns freely in the die.

I claim—

The combination of the reversible cutter adapted to cut at either of its two opposite edges, the bearing-block, for one of such cutting-edges to rest against, the yoke arranged within and going through the said cutter, and finally the clamping-screw going through and bearing against the block and screwed into the yoke at its middle, the cutter being revolvable on the yoke, and all being arranged in manner and to operate substantially as set forth.

BAILEY WHITE GEARY.
